UNITED STATES PATENT OFFICE.

JAMES R. MOFFATT AND RALPH S. KELSO, OF CHICAGO, ILLINOIS, ASSIGNORS TO UNION SPECIAL MACHINE COMPANY, OF CHICAGO, ILLINOIS, A CORPORATION OF ILLINOIS.

FEEDING MECHANISM FOR SEWING MACHINES.

Application filed September 26, 1917. Serial No. 193,363.

To all whom it may concern:

Be it known that we, JAMES R. MOFFATT, and RALPH S. KELSO, citizens of the United States, residing at Chicago, in the county of Cook, State of Illinois, have invented certain new and useful Improvements in Feeding Mechanism for Sewing Machines, of which the following is a description, reference being had to the accompanying drawing and to the figures of reference marked thereon.

This invention relates to new and useful improvements in feeding mechanism for sewing machines, and more particularly to a feeding mechanism having a lower feed dog engaging the under face of the fabric and an upper feed dog which cooperates therewith and engages the upper face of the fabric.

This invention embodies specific improvements on our copending application 131,223 filed November 14, 1916, for feeding mechanism for sewing machines.

In the above mentioned application a top feed dog was positively moved up and down and back and forth in a substantially four-motion path of travel, and by reason of the positive driving connections for said feed dog, the latter necessarily pounded to a considerable extent on the lower feed dog when partaking of its downward movement.

The principal object of this invention is therefore to provide a mechanism for imparting a four-motion path of travel of the upper feed dog, and including in the driving connections therefor, a cushioning arrangement which will greatly reduce the pounding of said upper feed dog as above noted.

These and other objects will in part be obvious and will in part be more fully disclosed.

In the drawings which show by way of illustration one embodiment of the invention—

Figure 1 is a view partly in end elevation and partly in vertical section showing a sewing machine embodying our improvements, the upper and lower feed dogs being shown engaging the fabric;

Figure 2 is a similar view showing the feed dogs respectively raised and lowered for their return movements, the presser foot clamping the fabric to the work support;

Figure 3 is a rear elevation of the sewing machine;

Figure 4 is an enlarged perspective view showing the mechanism for imparting the four motion path of travel to the upper feed dog, said mechanism including the cushioning device; and

Figure 5 is a detail vertical sectional view through the cushioning device for the upper feed dog.

In carrying out our invention, we have provided a lower feeding mechanism which includes a main or lower feed dog which is given the usual four-motion path of travel. Cooperating with this lower feed dog is an upper feed dog or feeding foot and also a presser foot. The upper feed dog is given its backward and forward movement through a train of mechanisms connected with the mechanism for giving the lower feed dog its back and forward movements, so that said upper and lower feed dogs are timed together in their backward and forward movements. The up and down movements to the upper feed dog are obtained through a train of mechanism from an eccentric on the main shaft of the machine, and the connection with this eccentric is adjustable to permit of the timing the up and down movements of said upper feed dog to be varied. This last mentioned train of mechanism includes a rocking lever, and a connection between one arm of said lever and the bar which supports the upper feed dog so that upon rocking movement of said lever the upper feed dog will be given its up and down movements. This connection between the rocking lever and said feed bar includes a loose and yieldable device whereby when the foot is moved downwardly to engage the fabric said yieldable device will yield under the positive action of the rocking lever and thereby greatly lessen the pounding of said upper feed dog on the under feed dog.

Referring more in detail to the drawings—

We have shown our improvements as applied to a sewing machine having a supporting bed 1 carrying an overhanging arm 2 in which a needle bar 3 reciprocates. Said needle bar is provided, as shown, with needles 4—4. This needle bar is reciprocated in the usual way. Cooperating with the

needles below the work support are loopers 5—5 which are oscillated in the usual manner. These parts are of the usual construction and form no part of the present invention.

5 A work support 6 is carried by the supporting bed 1 and is provided with a feed slot 7 through which the main or lower feed dog 8 operates. The material is held on the 10 work support between feeding movements by a presser foot 9, and this foot is carried by a presser bar 10 mounted to move vertically only in the overhanging arm 2.

Cooperating with the main or lower dog 15 8 is an upper feed dog 11. The lower feed dog is carried by a feed bar 12 and this bar is reciprocated by a feed rocker 13 to impart the backward and forward movements to said feed dog. The feed rocker is reciprocated in the usual manner from the main 20 shaft 14. The feed bar 12 is raised and lowered by an eccentric 15 fixed to the main shaft 14.

The upper feed dog 11 is clamped to the 25 lower end of a vertically disposed feed bar 16. The upper end of this bar is provided with a slot 17 which has sliding engagement with a fulcrum pin 18 fixed to the overhanging arm 2. This permits the bar to reciprocate vertically and also to swing about said pin 18. The feed bar 16 is also provided with an opening 19; and a bearing plate 20, larger than the opening, spans the same, and is secured to the overhanging arm 30 2 by a screw 21. This opening 19 is of sufficient size to permit the feed bar 16 to move up and down and back and forth at this point.

The feed bar 16 is oscillated about the pin 40 18 by a train of mechanism which includes a reciprocating lever 22, a link 23 pivotally connecting said lever with said feed bar, and suitable driving connections between the lever and the feed rocker 13 said parts 45 being arranged whereby the back and forth movements of the upper feed dog will be timed with the back and forth movements of the lower feed dog.

Fixedly secured to the presser bar 10 is 50 a guide arm 24, and this guide arm is in turn fixedly connected to a guide bar 25 which is movable vertically in suitable bearings in the overhanging arm. The guide arm 24 serves to prevent oscillations of the presser bar 10 and also causes the guide bar 55 25 to be moved vertically with said presser bar.

The upper feed bar 16 is reciprocated in a vertical plane through a train of mechanism which includes a reciprocating lever 60 26 which is in turn actuated from an eccentric on the main shaft 14. The lever 26 is connected by a link 27 to the lower end of the vertical arm 28 of a rocking lever 29. 65 This rocking lever is pivoted at its fulcrum,

as at 30, to a block 31 which is rigidly clamped to the presser guide bar 25. One end of this block 31 has sliding engagement with the presser bar 10 to maintain said block against oscillatory movement about 70 said guide bar 25. The horizontal arm 32 of said rocking lever is connected to the upper feed bar 16 by a connection which will impart up and down movements to the upper foot 11 upon oscillatory movements 75 of said rocking lever 29. This connection is a two-part connection and includes a loose connection between the parts, and also a yielding device disposed between said parts to cushion the downward movement of the 80 upper feed dog. This connection includes upper and lower tubes 33 and 34 respectively which are arranged in telescopic relation, the lower tube being disposed within the upper tube. The upper end of the upper tube is closed and is pivotally connected by a pin 35 to the outer end of the horizontal arm 32 of said rocking lever 29. The lower end of the lower tube 34 is closed and is pivotally connected by a pin 36 to the 85 upper feed bar 16. A vertically disposed slot 37 is located in the upper tube 33 and a stop screw 38 is arranged within this opening and threaded into the lower tube 34. The slot 37 is of a length sufficient to 90 permit the screw to have vertical movements for a limited distance. This connection between the upper and lower tubes forms a loose but positive connection therebetween. Disposed within the lower tube 34 is a coiled 10 spring 39 which normally extends above the upper edge thereof and bears against the closed end of the upper tube 33. This spring normally acts to urge the upper and lower tubes apart, but the movement is of 10 course limited by the screw 38 engaging the wall of the slot 37.

From the foregoing it will be noted that the oscillations of the lever 26 will through the link 27, impart oscillatory movements 11 to the rocking lever 29. As the horizontal arm 32 of said rocking lever moves downwardly to lower the top feed dog 11 onto the fabric, said downward movement of the arm 32 will be cushioned by the spring 39 as 1 soon as the foot 11 engages the fabric, and thereby practically eliminate any pounding of the top feed dog against the under feed dog. Upon continued movement of the arm 32 of said rocking lever the pivot thereof 1 is changed from the fulcrum 30 to the pivot pin 35, and as a result the presser foot 9 through the rigid connections between the presser bar 10, fulcrum 30 and block 31 will cause the presser foot to be elevated. Before the feed dogs begin their return movements the foot is caused to move downwardly to engage and clamp the fabric against the work support, and immediately following said clamping action, the two feed 1

dogs are simultaneously returned. As a result the fabric is alternately clamped between the presser foot and work support for the two feed dogs.

5 By means of this cushioning connection the pounding of the upper feed dog on the under feed dog which necessarily results in considerable noise and also in considerable breakage to the under feed dog, is practically eliminated.

Having thus described our invention, what we claim as new, and desire to secure by Letters Patent, is:

1. A feeding mechanism for sewing machines including an upper feed dog, a feed bar, a feed dog rigidly connected to the lower end of said feed bar, means for moving the lower end of the feed bar back and forth for imparting feeding movements to the feed dog, and means for moving the feed bar up and down including a pivoted opening connection with said feed bar whereby said bar may move freely back and forth.

2. A feeding mechanism for sewing machines including an upper feed dog, a feed bar for supporting said dog, means for moving said dog back and forth, and means for moving said dog up and down including a rocking lever and a yieldable connection between said lever and said feed dog support, said connection being independent of the support and including two parts telescopically arranged, a pin and slot connection between said parts for limiting their relative movements, and a spring interposed between said parts.

3. A feeding mechanism for sewing machines including an upper feed dog, a vertically disposed feed bar carrying said feed dog, means for supporting the upper end of said feed bar whereby it may be oscillated and bodily raised and lowered, means for positively swinging said feed bar for moving the feed dog back and forth, a rock

lever having a vertically disposed arm and a horizontally disposed arm, means connected to said vertically disposed arm for oscillating said rock lever, a link for connecting the horizontally disposed arm to said feed bar, said link including two telescoping parts, a pin and slot connection between said parts for limiting their relative movements, and a spring interposed between said parts.

4. A sewing machine including in combination, a work support, a feed dog disposed beneath said work support, means for moving said feed dog back and forth and for raising and lowering the same, the upper feed dog constituting the sole feeding member for engaging the upper face of the fabric, a vertically disposed feed bar to which said feed dog is rigidly connected, means for supporting the upper end of said feed bar whereby it may be swung for imparting feeding movements to the feed dog and whereby it may be raised and lowered, means for positively swinging the feed bar, a rock lever, said rock lever having a horizontally disposed arm, a link pivotally connecting the horizontally disposed arm with the feed bar for raising and lowering the same, means adjacent the lower end of the feed bar for guiding the same in its back and forth and up and down movements, said link including a yielding means having a positive limitation whereby the feed bar may be positively raised from engagement with the fabric and yieldingly forced against the fabric when lowered.

In testimony whereof, we affix our signatures, in the presence of two witnesses.

JAMES R. MOFFATT.
RALPH S. KELSO.
